UNITED STATES PATENT OFFICE.

KATHLEEN S. COOK, OF EASTON, PENNSYLVANIA.

SKEIN-HOLDER.

1,310,741.

Specification of Letters Patent.

Patented July 22, 1919.

Application filed March 15, 1918. Serial No. 222,540.

To all whom it may concern:

Be it known that I, KATHLEEN S. COOK, a citizen of the United States, residing at Easton, in the county of Northampton and State of Pennsylvania, have invented a certain new and useful Improvement in Skein-Holders, of which the following is a specification.

My invention relates to skein winders, and has for its object to provide a simple and convenient device for holding a hank or skein of worsted or yarn while it is being rolled into a ball.

At the present time an enormous amount of knitting is being done by the women of the country and practically all the yarn suitable for knitting is supplied to them in hanks or skeins and must be rolled into balls before being used.

20 While being rolled into a ball the skein must be supported in an open position as is well known either by being held on the hands of a second person or on the back of a chair or in some similar manner.

25 The object of my present invention, therefore, is to provide a support having the advantageous features hereinafter described and claimed; to provide an adjustable skein holder which may be assembled readily and 30 when dis-assembled may be contained in very small space, and which when in use is rigid and convenient to use.

With the above and other objects in view, my invention consists in the features of construction described in the following specification and shown on the accompanying drawing, forming a part hereof.

Referring to the drawing,

Figure 1 shows a skein supporter embodying my invention;

Fig. 2, the hub supporting the radial arms;

Fig. 3, the central support for the hub;

Fig. 4, the base;

45 Fig. 5, one of the radial arms; and

Fig. 6, one of the pins inserted in the radial arms.

Referring more in particular to the drawings, in Fig. 1, *a* is the base or support shown separately in Fig. 4, and *b* a central support secured in the base *a* by means of the stem *c* fitting in the socket *d*.

On the top of support *b* is the pivot *e* on which is mounted so as to be free to 55 rotate the hub *f*.

This hub is provided with a number of sockets or recesses *g* into which are fitted the removable arms *h* carrying the pins *j* adjustable in the holes *k* at greater or less distance from the pivot *e* to suit the varying sizes of the skeins of worsted *l* while being rolled into the ball *m*.

This base *a* should be of suitable size to give the necessary stability to the device when in use and if desired may be given additional stability by means of additional weight.

The hub *f* has the sockets or recesses *g* preferably of a dovetailed form, the inner ends of the arms *h* being of a dovetailed form to match, in order that the arms *h* may be retained in position in the hub *f*.

The holes *k* in the arms *h* for pins *j* should have a slight outward inclination so as to more securely hold the skein.

In this manner I provide a convenient device for holding yarn while being wound into balls and one which can readily be taken apart by any one and reduced to a very small compass for carrying around. It is often desirable to carry this device to a gathering where wool is to be wound and by my construction it can be reduced to a very compact bundle and at the same time forms a substantial and rigid construction when assembled.

It is to be understood that the present showing and description disclose only one specific embodiment of my present invention, and that other forms and modifications are included within the spirit and scope of the invention, as expressed in the appended claims.

Having thus described my invention, what I claim is:

1. In a skein supporter, a circular disk-shaped hub rotatably pivoted upon a central support which is itself rotatably secured in a base, said hub having a plurality of radial slots dovetailed on their lateral edges, a plurality of rigid radial arms outstanding from said hub and having on their inner ends dovetailed surfaces fitting said dovetailed slots on the hub and detachable pins projecting at an outward angle from the upper surface of said arms at their extremities to support and hold the skein while it is being wound.
2. In a skein supporter, a circular disk-shaped hub rotatably pivoted upon a central

support which is itself rotatably secured in a base, said hub having a plurality of radial slots dovetailed on their lateral edges, a plurality of rigid radial arms outstanding from said hub and having on their inner ends dovetailed surfaces fitting said dovetailed slots on the hub and detachable pins projecting at an outward angle from the upper surface of said arms at their ⁵ extremities to support and hold the skein while it is being wound, the said pins being adapted to be readily withdrawn from the

radial arms, the arms being adapted to be readily withdrawn from the hub, the hub readily withdrawn from the rotatable support and the rotatable support readily withdrawn from the base, whereby the whole structure in its normal inoperative position is entirely disassembled, each part separate from the other so that it may be compactly ¹⁵ contained within a small place. ²⁰

In testimony whereof, I have hereunto set my hand.

KATHLEEN S. COOK.
